CLAIM

The ornamental design for a carrying case for food items, as shown and described.

DESCRIPTION

FIG. 1 is a perspective view of a carrying case for food items when closed showing my new design;
FIG. 2 is a front elevational view thereof;
FIG. 3 is a rear elevational view thereof;
FIG. 4 is a top view thereof;
FIG. 5 is a bottom view thereof;
FIG. 6 is a right side elevational view with the left side being a mirror image thereof; and,
FIG. 7 is an environmental perspective view of a carrying case for food items when open showing my new design.

FIG. 1

FIG. 2

FIG. 3

FIG. 4

FIG. 5

FIG. 7
